(57) **CLAIM**

The ornamental design for a display screen or portion thereof with graphical user interface, as shown and described.

DESCRIPTION

The file of this patent contains at least one drawing/photograph executed in color. Copies of this patent with color drawing/photograph will be provided by the Office upon request and payment of necessary fee.

FIG. 1 is a front view of a display screen or portion thereof with graphical user interface showing our new design in accordance to a first embodiment;

FIG. 2 is a front view of a display screen or portion thereof with graphical user interface showing our new design in accordance to a second embodiment; and,

FIG. 3 is a front view of a display screen or portion thereof with graphical user interface showing our new design in accordance to a third embodiment.

The broken lines in the figures show a display screen or portion thereof, and form no part of the claimed design.
